US0D1111920S

(12) **United States Design Patent** (10) Patent No.: **US D1,111,920 S**
(45) Date of Patent: ** Feb. 10, 2026

(54) **VEHICLE HEADLIGHT**

(71) Applicants: **Rivian IP Holdings, LLC**, Plymouth, MI (US); **Amazon Technologies, Inc.**, Seattle, WA (US)

(72) Inventors: **Stephen Mark Goodrich**, Southfield, MI (US); **Luke James Mack**, Newport Beach, CA (US); **Nicholas Adam Malachowski**, Bloomfield Hills, MI (US); **John Sokol**, Sammamish, WA (US); **Ross Rachey**, Bellevue, WA (US); **Benjamin Hewitt**, Seattle, WA (US); **Christopher Gordon**, Bellevue, WA (US)

(73) Assignees: **Rivian IP Holdings, LLC**, Plymouth, MI (US); **Amazon Technologies, Inc.**, Seattle, WA (US)

(**) Term: **15 Years**

(21) Appl. No.: **29/889,091**

(22) Filed: **Apr. 7, 2023**

Related U.S. Application Data

(63) Continuation of application No. 29/853,624, filed on Sep. 16, 2022, now Pat. No. Des. 1,008,123, which is a continuation of application No. 29/722,849, filed on Feb. 2, 2020, now Pat. No. Des. 964,898.

(57) **CLAIM**

The ornamental design for a vehicle headlight as shown and described.

DESCRIPTION

FIG. 1 is a front-right corner perspective view of a vehicle headlight showing the claimed design;

FIG. 2 is a front view of the vehicle headlight;

FIG. 3 is a front-left corner perspective view of a vehicle headlight showing the claimed design;

FIG. 4 is a left-side view of the vehicle headlight; and,

FIG. 5 is a top view of the vehicle headlight.

Features of the vehicle rendered in broken lines surrounding the vehicle headlight form no part of the claimed design, and the dashed-dot line shows a boundary of the unclaimed portion of the vehicle and forms no part of the claimed design.

1 Claim, 5 Drawing Sheets
